(57) **CLAIM**

The ornamental design for a golf putting game kit, as shown and described.

DESCRIPTION

FIG. 1 is a top plan view of a golf putting game kit showing our new design showing a mat, a score card, a plurality of numbered cards, a putter, a plurality of chips, and a ball separated for clarity;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is an isometric view thereof.

The broken away symbols in the drawings indicate the appearance of any portion of the article between the break lines forms no part of the claimed design.

The broken line showing of the numbers 1 and 10 on the mat are included for the purpose of illustrating and forms no part of the claimed design.

1 Claim, 5 Drawing Sheets

FIG. 1

FIG. 2

FIG. 4

FIG. 3
